VICTOR M. PIECHOCINSKI, OF NEW YORK, N. Y.

STATION-INDICATOR.

1,074,457.

Specification of Letters Patent. Patented Sept. 30, 1913.

Application filed April 4, 1913. Serial No. 758,797.

To all whom it may concern:

Be it known that I, VICTOR M. PIECHOCINSKI, a subject of the Emperor of Austria-Hungary, and a resident of the city of New York, borough of Manhattan, in the county and State of New York, have invented a new and Improved Station-Indicator, of which the following is a full, clear, and exact description.

10 The object of the invention is to provide a new and improved station indicator for use in railway cars, street cars and other cars and vehicles running over predetermined routes, and arranged to require no resetting by the person in charge of the car, and to enable such person to quickly and conveniently manipulate the indicator with a view to correctly display the name of the next station within the car during the outgoing 15 trip and the return trip of the car over the route.

In order to accomplish the desired result, use is made of a web bearing the names of the station along the route, a spring roller, 25 an actuating roller, the web being connected at its ends with the said rollers to impart a traveling motion to the web in either direction on turning the said actuating roller in either direction, and a manually-controlled mechanism having automatic reversing means for 30 turning the said actuating roller in one direction until the end of the route is reached by the car, and to turn the actuating roller in the reverse direction during the return 35 trip of the car over the route without requiring the resetting of the station indicator.

A practical embodiment of the invention is represented in the accompanying drawing forming a part of this specification, in which 40 similar characters of reference indicate corresponding parts in all the views.

Figure 1 is a front elevation of the station indicator with the front of the casing removed and parts shown in section; Fig. 2 is 45 a transverse section of the same on the line 2-2 of Fig. 1; Fig. 3 is a like view of the manually-controlled actuating device with parts in a different position; Fig. 4 is a cross section of a portion of the automatic reversing mechanism, the section being on the line 4-4 of Fig. 5; Fig. 5 is a sectional plan view of the station indicator on the line 5-5 of Fig. 2; Fig. 6 is a front elevation of the reversing means with the parts in a different position from the one shown in Fig. 51; Fig. 7 is a cross section of the pawl and

ratchet mechanism on the driving shaft, the section being on the line 7-7 of Fig. 1; and Fig. 8 is a similar view of part of the driving and reversing mechanism on the line 8-8 of Fig. 1.

Within a suitably constructed casing A are arranged two rollers B and C, on which winds and unwinds a web D bearing the names E of the stations along the route over

which the car is to travel in both directions.

The roller B is located a distance above the roller C and the web D is held stretched between the rollers. The roller B is the actuating roller for winding up and unwinding

the web D, as hereinafter more fully explained. The roller C is a spring-pressed roller of any approved construction, capable of winding up the web D at the time the actuating roller B is turned in one direction

70 to unwind the web D, and the said spring roller C allowing the web D to unwind at the time the actuating roller B is turned in the opposite direction to wind up the web D.

During the unwinding of the web D from the spring roller C the spring thereof is placed under tension. The name E of an approaching station registers with a window A' formed in the front of the casing A so that the passengers in the car can read the

85 name of the next station.

In practice, two station indicators of like construction are used, one at each end of the car, and operated simultaneously, as herein-after more fully explained.

90 The actuating roller B is provided with a shaft B' journaled in suitable bearings in the casing A, and on the left-hand end of the shaft B' is secured a gear wheel B² adapted to be engaged by a gear wheel F mounted to

turn with and to slide on a driving shaft G journaled in suitable bearings arranged in the casing A. The gear wheel B² is also adapted to be engaged by a gear wheel F' in mesh with a gear wheel F² mounted to turn

95 with and to slide on the driving shaft G in harmony with the gear wheel F. The gear wheel F' is of sufficient width to be in mesh at the same time with the gear wheel B² and the gear wheel F², as plainly indicated in

100 Fig. 1. When the driving shaft G is rotated in the direction of the arrow a' (see Fig. 8), and the gear wheel F is out of mesh with the gear wheel B² and the gear wheel F' is

105 in mesh with the gear wheel B², then a rotary motion is given by the gear wheels F², F' and B² to the roller shaft B' to rotate the

90

95

100

105

110

latter in the direction of the arrow b' whereby the web D is wound up on the actuating roller B and unwound from the spring roller C. When the gear wheels F, F', F² are shifted from the left to the right into the position shown in Fig. 6 then the rotary motion of the shaft G in the direction of the arrow a' is transmitted to the roller shaft B' in the inverse direction of the arrow b' by the gear wheel F being now in mesh with the gear wheel B² while the gear wheel F' is out of mesh with the gear wheel B². When this takes place the web D unwinds from the actuating roller B and is wound up by the spring roller C.

In order to rotate the driving shaft G in the direction of the arrow a' , the following arrangement is made: On the driving shaft G is mounted to rotate loosely a gear wheel H in mesh with a rack I mounted to slide transversely in the top of the casing A (see Figs. 1, 2, 3 and 5). The rack I is normally held in a forward position by the action of a spring I' attached at one end to the casing and at the other end to the rack I, and to the rear end of the rack I is secured a rope, cable or other connection I² under the control of the person in charge of the car to permit such person to slide the rack I rearwardly against the tension of the spring I' with a view to rotate the gear wheel H in the direction of the arrow a' . When the person in charge of the car releases the pull on the connection I² then the rack I returns to normal forward position by the action of the spring I'. On one face of the gear wheel H is secured an arm H' carrying a pawl H² in engagement with the peripheral face of a ratchet wheel H³ having a single tooth H⁴ (see Fig. 7). The ratchet wheel H³ is keyed or otherwise fastened to the shaft G, and when the gear wheel H is rotated on moving the rack I rearwardly in the direction of the arrow c' (see Fig. 2) then the pawl H² finally engages the tooth H⁴ and turns the ratchet wheel H³ in the direction of the arrow a' thus rotating the shaft G in the same direction. The rack I is of such length that during its full rearward movement a complete turn is given to the shaft G, and when the rack I returns to its normal forward position then the pawl H² glides over the peripheral face of the ratchet wheel H³ without turning the same. When the rack I has reached its normal position the pawl H² is a distance in front of the tooth H⁴, as plainly indicated in Fig. 7.

The shaft G is normally held in a locked position and for this purpose the following arrangement is made: On the shaft G is secured a locking wheel J provided with a peripheral notch J' adapted to be engaged by a friction roller J² journaled on a vertically-disposed rod J³ mounted to slide verti-

cally in a suitable bearing A² attached to the top of the casing A (see Fig. 2). The rod J³ is pressed on by a spring J⁴ to normally hold the roller J² in engagement with the notch J' to prevent accidental turning of the shaft B. The rod J³ is provided with a pin J⁵ adapted to be engaged by an arm J⁶ pivoted on the rack I and moving with the same. When the rack I is in normal front position the free end of the arm J⁶ extends under the pin J⁵ and when the rack I is moved rearwardly in the direction of the arrow c' , as previously explained, then the arm J⁶ lifts the pin J⁵ and with it the rod J³ so that the roller J² moves out of engagement with the notch J' to unlock the locking wheel J at the time the pawl H² has reached the tooth H⁴ (see Fig. 3). Shortly after the shaft G has begun to rotate the pivotal end of the arm J⁶ passes from under the pin J⁵ so that the friction roller J² now engages and travels on the peripheral face of the locking wheel J, and when the shaft G has made a complete revolution the rod J³ is pressed downward by its spring J⁴ to re-engage the friction roller J² with the notch J'. During the subsequent return movement of the rack I the arm J⁶ moves into engagement with the top of the pin J⁵ and is swung upward to allow the arm J⁶ to ride on the pin J⁵ until the rack I reaches its normal forward position and when this takes place the arm J⁶ swings downward into position to reengage the under side of the pin J⁵ on the next rearward movement of the rack I.

The driving and reversing gear consisting of the gear wheels F, F', F² is automatically shifted from the roller shaft B' and relatively to the gear wheel B² of the said roller shaft. For this purpose the following arrangement is made: On the roller shaft B' is secured a gear wheel K in mesh with a gear wheel K' attached to an intermediate shaft K² journaled in suitable bearings in the casing A, and arranged parallel to the roller shaft B'. A gear wheel L having the flanges L' is mounted to turn with and to slide lengthwise on the shaft K² by the use of a key K³ held on the shaft K² and engaging a keyway in the gear wheel L. The gear wheel L is in mesh with a gear wheel N' formed on the peripheral face of a nut N screwing on a traverse screw O supported in the casing A. The gear wheel N' extends between the flanges L' of the gear wheel L and when the shaft K² is driven from the shaft B' then the gear wheel L rotates the gear wheel N' and in doing so causes the nut N to screw on the traverse screw O whereby the gear wheel L is carried along and shifted in the same direction in which the nut N is traveling at the time on the traverse screw O. On the faces of the nut N are arranged lugs N², N³

of which the lug N^2 is adapted to engage an arm P while the lug N^3 is adapted to engage an arm P' , the arms P and P' being secured to a rock shaft P^2 journaled in suitable bearings arranged within the casing A .
 5 On the rock shaft P^2 is secured a pin P^3 projecting into a fork Q' of a shifting lever Q pivoted at Q^2 in the casing A . The shifting lever Q is provided with a shifting fork Q^3 engaging an annular groove F^3 in the hub F^4 common to both gear wheels F and F^2 (see Fig. 5). The intermediate gear wheel F' has its shaft F^5 journaled in arms F^6 held loosely on the driving shaft G , the arms F^6 extending close to the outer faces
 10 of the gear wheels F , F^2 . When the gear wheel nut N moves to the left its lug N^2 engages the arm P at the time the car has reached the second last station on the route,
 15 and when the operator actuates the station indicator to display the last station within, the lug N^2 imparts a swinging motion to the arm P to rock the shaft P^2 which by the pin P^3 imparts a swinging motion to
 20 the shifting lever Q to shift the gear wheels F , F' , F^2 from the position shown in Fig. 1 into the position shown in Fig. 6, whereby the gear wheel F' moves out of mesh with the gear wheel B^2 and the gear wheel F
 25 moves in mesh with the gear wheel B^2 . When the shaft G is next rotated on the operator manipulating the rack I , as previously explained, then the actuating roller shaft B' is turned in the opposite direction
 30 to wind up the web D on the roller B , that is, so as to display the stations E in the reverse order during the return trip of the car. When the car reaches the second last station on the return trip the gear wheel
 35 nut N has traveled to the right so that the lug N^3 is in engagement with the arm P' , and when the car travels to the first station and the operator actuates the shaft G , as previously explained, then the lug N^3 imparts a swinging motion to the arm P' to rock the shaft P^2 in the reverse direction so that the pin P^3 imparts a return swinging motion to the shifting lever Q to move the gear wheels F , F' , F^2 back to the original
 40 position shown in Fig. 1. When the shaft B' is next turned, the web D again unwinds from the roller B and is wound up by the spring roller C during the next outgoing trip of the car.
 45 The operation is as follows: When the several parts are in the position shown in Figs. 1, 2 and 5, the car is on the outgoing trip, and when the car leaves a station the operator in charge of the car pulls the flexible connection I^2 to cause the shaft G to become unlocked and to rotate, as previously explained, and a rotary motion is transmitted by the gear wheels F^2 , F' and B^2 to the shaft B' and consequently the roller B to
 50 wind up the web D on the said roller B .
 55

The name E now in register with the window A' is that of the next station. The above operation is repeated for each station along the route, and when the second last station has been passed and the operator
 70 causes the shaft G to rotate then the lever Q is actuated as above explained to shift the gear wheels F , F' , F^2 from the position shown in Figs. 1 and 5 to that shown in Fig. 6, whereby the next rotation given to
 75 the shaft G causes the shaft B' and the roller B to rotate in the reverse direction of the arrow b' so that the web D unwinds from the roller B and winds up on the roller C .
 80 From the foregoing it will be seen that during the return trip of the car the names of the stations are displayed in the same manner as above described during the outgoing trip and no re-setting whatever of the mechanism by the operator in charge is required. Should the car for any reason not travel the entire length of its route and is compelled to return then the operator in charge can actuate the shifting lever Q to provide a reverse movement of the actuating roller B . For the purpose mentioned the shifting lever Q is provided with a handle Q^5 extending through a slot A^3 in the bottom of the casing so that the handle Q^5 is within reach of the operator.
 85

Having thus described my invention, I claim as new and desire to secure by Letters Patent:

1. In a station indicator for cars, the combination of a web having the names of the stations along a predetermined route, a spring roller, an actuating roller, the rollers being spaced apart and connected with the ends of the web so that when the actuating roller is turned in one direction the web unwinds from the actuating roller and winds up on the spring roller, and when the actuating roller is turned in the opposite direction the web is wound up by the actuating roller and unwinds from the spring roller, and a manually-controlled turning mechanism for the said actuating roller and provided with shiftable reversing means for turning the actuating roller in the direction to unwind the web while the car is on the outgoing trip and to turn the actuating roller in the direction to wind up the web while the car is on the return trip, a shifting lever connected with the reversing means to shift the latter, a rock shaft, a connection between the rock shaft and the shifting lever to actuate the latter, and means driven from the shaft of the actuating roller and controlling said rock shaft, the said shifting lever having a handle extending within reach of the operator.

spring roller, an actuating roller, the rollers being spaced apart and connected with the ends of the web so that when the actuating roller is turned in one direction the web unwinds from the actuating roller and winds up on the spring roller, and when the actuating roller is turned in the opposite direction the web is wound up by the actuating roller and unwinds from the spring roller, a driving shaft, manually-controlled means for rotating the said driving shaft in one direction only, a roller shaft carrying the said actuating roller, shiftable gearing connecting the said driving shaft with the said roller shaft to rotate the latter and its actuating roller in either direction, an intermediate shaft driven from the said roller shaft, a traverse screw, a gear wheel nut screwing on the said traverse screw, a gear wheel mounted to turn with and to slide lengthwise on the said intermediate shaft and engaging the said gear wheel nut to turn the latter and to travel with the same, and a shifting mechanism connected with the said shiftable gearing and controlled by said gear wheel nut.

3. In a station indicator for cars, the combination of a web bearing the names of the stations along a predetermined route, a spring roller, an actuating roller, the rollers being spaced apart and connected with the ends of the web so that when the actuating roller is turned in one direction the web unwinds from the actuating roller and winds up on the spring roller, and when the actuating roller is turned in the opposite direction the web is wound up by the actuating roller and unwinds from the spring roller, a driving shaft, manually-controlled means for rotating the said driving shaft in one direction only, a roller shaft carrying the said actuating roller, shiftable gearing connecting the said driving shaft with the said roller shaft to rotate the latter and its actuating roller in either direction, an intermediate shaft driven from the said roller shaft, a traverse screw, a gear wheel nut screwing on the said traverse screw, a gear wheel mounted to turn with and to slide lengthwise on the said intermediate shaft and engaging the said gear wheel nut to turn the latter and to travel with the same, a rock shaft provided with arms spaced apart and located on opposite sides of the said gear wheel nut, lugs on opposite faces of the said gear wheel nut and adapted to alternately engage the said arms at the time the gear wheel nut nears either end of the traverse screw, a pin on the said rock shaft, and a shifting lever engaged by the said pin and connected with the said shiftable gearing to shift the latter.

4. In a station indicator for cars, the combination of a web bearing the names of the stations along a predetermined route, a

spring roller, an actuating roller, the rollers being spaced apart and connected with the ends of the web so that when the actuating roller is turned in one direction the web unwinds from the actuating roller and winds up on the spring roller, and when the actuating roller is turned in the opposite direction the web is wound up by the actuating roller and unwinds from the spring roller, a roller shaft carrying the said actuating roller, a driving shaft, reversible gearing connecting the said driving shaft with the said roller shaft for driving the latter in either direction, a one-tooth ratchet wheel secured on the said driving shaft, a gear wheel loose on the said driving shaft and carrying a pawl engaging the said ratchet wheel, and a manually-controlled rack mounted to slide and in mesh with the said loose gear wheel.

5. In a station indicator for cars, the combination of a web bearing the names of the stations along a predetermined route, a spring roller, an actuating roller, the rollers being spaced apart and connected with the ends of the web so that when the actuating roller is turned in one direction the web unwinds from the actuating roller and winds up on the spring roller and when the actuating roller is turned in the opposite direction the web is wound up by the actuating roller and unwinds from the spring roller, a roller shaft carrying the said actuating roller, a driving shaft, reversible gearing connecting the said driving shaft with the said roller shaft for driving the latter in either direction, a one-tooth ratchet wheel secured on the said driving shaft, a gear wheel loose on the said driving shaft and carrying a pawl engaging the said ratchet wheel, a locking wheel secured on the said shaft, a spring-pressed locking arm adapted to engage the said locking wheel to hold it against rotation, and a swing arm on the said rack and adapted to engage the said locking arm to lift the latter out of locking position prior to the pawl engaging the tooth of the said ratchet wheel.

6. In a station indicator for cars, the combination of a web bearing the names of the stations along a predetermined route, a spring roller, an actuating roller, the rollers being spaced apart and connected with the ends of the web so that when the actuating roller is turned in one direction the web unwinds from the actuating roller and winds up on the spring roller, and when the actuating roller is turned in the opposite direction the web is wound up by the actuating roller and unwinds from the spring roller, a roller shaft carrying the said actuating roller, a gear wheel on the said roller shaft, a manually-controlled driving shaft

- rotating in one direction only, a pair of spaced gear wheels mounted to turn with and to slide on the said driving shaft, one of the gear wheels of the said pair of spaced 5 gear wheels being adapted to engage the roller shaft gear wheel, an intermediate gear in mesh with the other gear wheel of the said pair of gear wheels and adapted to move into mesh with the said roller shaft gear 10 wheel, and an automatic shifting device actuated from the said roller shaft and connected with the pair of gear wheels and the said intermediate gear wheel to shift the same.
- 15 7. In a station indicator for cars, the combination of a web bearing the names of the stations, a spring roller, an actuating roller, the said web being connected with the said rollers, a shaft carrying said actuating 20 roller, a driving shaft, reversible gearing connecting the driving shaft with the roller shaft for driving the latter in either direction, to impart a traveling motion to the web in either direction, manually controlled 25 means for rotating the driving shaft in one direction, locking means for normally locking the driving shaft and controlled from

the said manually controlled means, and a shifting device for the reversible gearing operated from the actuating roller shaft. 30

8. In a station indicator for cars, the combination with a spring roller, an actuating roller, and a web bearing the names of stations, and connected with the said rollers, of a shaft carrying said actuating roller, a 35 driving shaft, manually controlled means for rotating the driving shaft in one direction only, shiftable gearing connecting the driving shaft with the said roller shaft for driving the latter and the actuating roller 40 in either direction, a shifting lever connected with the shiftable gearing to shift the latter, a rock shaft for actuating the shifting lever, and means driven from the shaft of the actuating roller, and controlling said 45 rock shaft.

In testimony whereof I have signed my name to this specification in the presence of two subscribing witnesses.

VICTOR M. PIECHOCINSKI.
